(57) **CLAIM**

The ornamental design for an industrial robot, as shown and described.

DESCRIPTION

FIG. 1 is a top, front, and side perspective view of an industrial robot, showing our new design according to a first embodiment;

FIG. 2 is a top, rear, and side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a first side view thereof;

FIG. 8 is a second side view thereof;

FIG. 9 is a top, front, and side perspective view of an industrial robot, showing our new design according to a second embodiment;

FIG. 10 is a top, rear, and side perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a first side view thereof; and,

FIG. 16 is a second side view thereof.

Broken lines indicate environmental structure that forms no part of the claimed design.

1 Claim, 6 Drawing Sheets
